(57) **CLAIM**

The ornamental design for a toy electric water gun as shown and described.

DESCRIPTION

FIG. 1 is a front, right and top perspective view of a toy electric water gun, showing my design.

FIG. 2 is a front, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 1; and,

FIG. 10 is an enlarged view of detail 10 in FIG. 2.

The evenly broken lines in the drawings depict portions of the toy electric water gun that form no part of the claimed design. The dot-dash broken lines in FIGS. 1-2 and 9-10 depict the boundaries of the enlargements which form no part of the claimed design.

1 Claim, 10 Drawing Sheets
